UNITED STATES PATENT OFFICE.

HUGH LONGBOURNE CALLENDAR, OF MONTREAL, CANADA.

ELECTRICAL RECORDING APPARATUS.

SPECIFICATION forming part of Letters Patent No. 642,674, dated February 6, 1900.

Application filed February 14, 1898. Serial No. 670,335. (No model.)

To all whom it may concern:

Be it known that I, HUGH LONGBOURNE CALLENDAR, a subject of the Queen of Great Britain, and a resident of McGill University, 5 in the city of Montreal, Dominion of Canada, have invented new and useful Improvements in Electrical Recording Apparatus, (for which I have filed an application for a patent in Great Britain, No. 16,718, dated July 14, 1897,) 10 of which the following is a specification.

The method of recording electrical quantities herein described is directly applicable to those cases in which the measurement may be effected by sliding a contact-piece along 15 the wire or other uniformly subdivisible resistance forming part of an electrical circuit until a point is found at which the value of the electric potential is the same as at some other given point. This equality of potential is ascertained by connecting a galvanometer or other suitable indicator between the points in question. The wire along which the readings are taken is called a "bridge-wire," and the point at which the current 20 through the galvanometer is reduced to zero is called the "balance-point." The bridge-wire is usually, but not necessarily, straight. Thus in cases where a higher resistance is required than can be obtained by the use of 25 a straight wire a close insulated helix wound on a rod may be employed with fifty or one hundred turns to the inch. This is practically equivalent to a straight bridge-wire, as the steps or subdivisions are so numerous as 30 to give a nearly-continuous adjustment. By attaching a pen or other recording device to the contact-piece on the bridge-wire and by moving the contact in such a manner as to keep it always at the balance-point it is clear 35 that the variations of the quantity to be measured may be recorded. The improvements herein described relate to means by which the contact is automatically maintained 40 always at the balance-point to the adjustment of the scale of the record and the construction of the apparatus in such a manner as to make the application as general and accurate as possible.

In order that my invention may be fully 45 understood, I will proceed to describe it with reference to the accompanying drawings, in which—

Figure I is a plan, and Fig. II an elevation, of the galvanometer arm and contacts. Figs. III and IV are a diagrammatic front elevation and end view of the instrument, showing the electrical connections. Fig. V is a diagram showing one arrangement of the driving-pulleys. Fig. VI is a diagram of a thermometer for measuring the voltage of alternating currents. Figs. VII and VII^a, Sheets 2 and 3, show a front elevation. Fig. VIII is a vertical section showing the mechanical construction of the instrument. Figs. IX and X are diagrams showing the electrical connections in two special cases.

In order to maintain the balance automatically, the galvanometer, which is preferably one of movable-coil type, is provided with an arm called the "relay-arm," which actuates 55 one or other of two electric circuits, according as the galvanometer deflects to one side or the other. The circuit so actuated starts a motor, which tends to restore the contact-piece to its position of balance. To prevent 60 sticking of the relay-contacts and to secure sufficient delicacy of action, the stop or stops with which the relay-arm makes contact are kept in a continual sliding motion, the contact-surfaces are also continually cleansed by 65 the action of suitable scrapers, and the relay-arm itself is kept in a state of gentle oscillation by means of a fan. The contact-stop is preferably made in the form of a slightly-eccentric wheel revolving by clockwork and 70 scraped on either side by a pair of light metal springs. The relay-arm 1 in Figs. I and II is shown with a pair of contacts 2 3, forming a fork on either side of the single contact-wheel 4; but it is equally possible to use a pair of 75 contact-wheels on either side of a single contact-point on the relay-arm. Scraping-springs of suitable form are shown at 5. The contact-wheel 4 is shown fixed to the spindle 15 of the seconds-hand of an ordinary lever-clock. The oscillating lever 16 of the escapement of this clock has fixed to it a small light plate 17, forming the fan, by which the arm 1 is kept in a state of oscillation. This 80 fan is only necessary when extreme sensitivity is required. The clearance between the wheel 4 and the contacts 2 and 3 is, say, one two-hundredth of an inch, and therefore the arm 1, if normally at rest, would have to be 85 90 95 100

deflected through that distance before any indication was given; but if the arm oscillates the contacts 2 and 3 alternately and momentarily touch the wheel 4. These contacts are so instantaneous that they produce little effect, and when the arm is normally central the effects are equal and balance each other; but if the arm 1 be deflected by the galvanometer, however slightly, the times during which the contacts with 2 and 3, respectively, last are no longer equal, and the effects, therefore, do not balance each other, and the effects produced by the difference are cumulative. In this way a deflection of the arm 1 greatly less than one two-hundredths of an inch is recorded.

The bridge-wire shown in Figs. III and VII is soldered at the ends to short pieces of thick wire A and B, which are held by set-screws 20 A' B' in the insulating-blocks EG FH. The bridge-wire itself is made of platinum silver or other suitable material having a resistance of one or two ohms per meter or more, if desired. Its resistance is adjusted to an exact 25 value by shunting it with a resistance S of similar material, which is adjusted so that the scales of different instruments may be commensurable. The bridge-wire may also take the form of a close spiral. The thick 30 wires A and B at either end serve for making connections and also for adjusting the zero-point of the wire with reference to the scale on the recording-sheets. For this purpose it is only necessary to slacken the set-screws 35 and move the wire endwise. When the bridge-wire is connected on the principle of "potentiometer," as described below, it is frequently desirable that the zero-point corresponding to zero difference of potential 40 should be at the center of the wire. It would not be always easy or convenient to make a connection to the center of the bridge-wire itself. The same effect is secured in a simple and exact manner by making connection 45 to the middle point of the shunt S. Connection is made between the bridge-wire and the galvanometer by means of a wire of similar material C D, which is called the "galvanometer-wire" and is stretched alongside the 50 bridge-wire. The sliding contact is preferably made by means of light springs carrying short pieces or rollers of platinum iridium, as shown at M N. These springs serve also to maintain a suitable pressure of the point 55 of the recording-pen P on the revolving drum O, Figs. VII, VII^a, and VIII. The pen and the contact-springs are attached to a sleeve KL, which slides along rod EF. The tension of the bridge-wire and galvanometer- 60 wire is maintained uniform by means of the metallic rods EF and GH, which are clamped in the insulating-blocks EG FH, but free to slide through holes in the block RT. The blocks EG RT are fixed to the base of the 65 instrument; but the block FH is free to slide. The traveling sleeve is provided with stops K and L, which engage with small spring-

switches V and W at either end of the travel. The switches V and W serve to break either electric circuit automatically and to prevent 70 the recording-point being carried off the limits of the scale, while leaving it free to return under the action of the opposite motor.

The mechanism for moving the contact-piece on the bridge-wire in either direction 75 according to the deflection of the galvanometer preferably consists of a pair of clock-motors connected by means of a suitable differential gear. This mechanism is shown in Figs. VII, VII^a, and VIII. a b are a pair of 80 electromagnets whose armatures a' b' are pivoted at a² b² and carry counterbalance-weights a³ b³ and have at their lower ends strips a⁴ b⁴, which serve as brakes acting on 85 brake-wheels c d, which are thus normally held stationary. These brake-wheels form part of two ordinary clock-trains without escapements, so that immediately one or other of the brakes is lifted by the magnet a or b attracting its armature the clock-train 90 starts. The movement of the relay-arm 1 in either direction, as shown in diagrams IX and X, closes a circuit from the battery e through one or other of the magnets a b, and this starts one or other clock-train, as above described. 95 f and g are the last pinions of the clock-trains, and these gear with wheels h and j, fixed to sleeves h' j', Fig. VIII, loose on the spindle k. h² j² are other wheels also fixed to the sleeves, and these gear with two pinions l l', which also gear together. The pinions l l' are carried by a frame l², fixed to the spindle k and provided with a counterbalance-weight l³. The action is as follows: If 100 the magnet a attracts its armature, the brake-wheel c and the wheel h² commence to rotate, while the wheel j² remains stationary, since the wheel d is still held by its brake. The revolution of the wheel h² drives the pinions l and l', the latter rolling around the stationary wheel j², and the frame l² and spindle k are thus slowly rotated. The spindle k is in like manner rotated, but in the opposite direction, when the magnet b attracts its armature. The spindle k has fixed to it a pinion 115 k', gearing with a wheel m', fixed to the drum or pulley m, around which passes the cord n, whose end is fixed to the spring K L. The same effect may also be produced by means of the differential system of pulleys shown in 120 Fig. V. In this diagram, 6 and 7 represent pulleys connected to the clock-motors so as to turn with suitable speed and power when the motors are released by the corresponding electromagnets. 8 and 9 are the differential 125 pulleys. 10 is an idle pulley attached to a spring for keeping the necessary tension on the cord. An endless cord passes around the pulleys 6 8 7 9 in order, as shown. The pulleys 8 and 9 are connected by a cord passing 130 around the pulley 10. It is plain on inspection that if the motor 6 starts to turn the pulley 9 is moved to the right and pulley 8 to the left, but that if the motor 7 starts in the same

direction the opposite takes place. The contact-piece on the bridge-wire may be connected to either of the pulleys 8 or 9, provided that the galvanometer connections are made 5 to correspond.

Connected to one end of the bridge-wire are a series of auxiliary resistances XYZ, &c., which are adjusted to represent "10," "20," "40," &c., or other suitable numbers of divisions of the scale of the bridge-wire. These resistances serve for extending the scale of the bridge-wire in the usual manner and are provided with plugs or screw-nuts, by means of which they can be short-circuited. For resistance measurements on the Wheatstone-bridge method a pair of ratio-coils QJ JU is also added. The galvanometer is then connected at J and M and the resistance to be measured at I and U. The place of these resistances may be supplied, if preferred, by ordinary commercial resistance-boxes. They are not essential parts of the apparatus; but it is generally convenient to include them in the same box.

25 The recording apparatus above described may be used for a variety of very different purposes without any modification in its essential features by connecting it to different pieces of apparatus or different electric circuits according to methods which are well understood. It is necessary, however, to specify these applications in order that some other inventor may not claim the combination as being a separate and distinct invention.

35 If the bridge-wire is connected, as shown in Fig. IX, in series with auxiliary resistances and suitable rheostat to constant battery *o*, the instrument may be used as a potentiometer for recording variations of electric potential. The difference of electric potential to be recorded would then be applied to the zero-point *p* on the auxiliary resistance or shunt and to the free terminal of the galvanometer *q*, (one terminal being already connected to the contact-point *M* on the bridge-wire.) The difference of potential to be measured may be that produced by a thermocouple *r*, in which case the record represents 45 variations of temperature, or may be some suitable fraction of the electric pressure on a direct-current lighting or power circuit, in which case the record gives directly the variations of the electric pressure. Variations 50 of current may be similarly recorded by the usual method of measuring the difference of potential on a known resistance through which the current is passed.

60 In order to record rapid cyclical variations of potential or current in the same manner, it is only necessary to include a periodic contact in the galvanometer-circuit to complete the circuit at a definite point of the cycle. If the point of the cycle corresponding to the 65 position of the contact-brushes be slowly and uniformly shifted, the recording-pen will trace the curve of the cycle. The forms of

alternating current and potential curves of dynamo-machines may be automatically traced in this manner. By means of a suitable thermopile the cyclical variations of temperature in the walls of the cylinder of a steam or other heat engine may be similarly recorded. In recording cyclical variations of this nature it is convenient to connect the 70 difference of potential to the middle point of the shunt in order that the zero may be at the center of the bridge-wire, as explained above.

A wide range of applications of this recording system is afforded by applying the instrument to record variations of electrical resistance. For this purpose the bridge-wire is connected on the Wheatstone-bridge method, as explained above. A battery *o* is connected 85 to the points Q U, as shown in Fig. X. This battery may conveniently be the same as that used for actuating the relay-circuit. If the resistance to be measured consists of an electrical resistance-thermometer *s*, the record will represent the variations of temperature of the thermometer and may be made to cover any desired range or to suit any desired purpose by choosing a thermometer of suitable resistance and construction. If an 90 alternating difference of potential be simultaneously applied to the thermometer and the wire be sufficiently fine to be heated by the current, the recorded variations of temperature of the resistance-thermometer will 95 give the variations of the alternating voltage. The variations of the alternating current may be recorded in a similar manner by passing the current or some suitable fraction thereof, through the wire of the thermometer. For 100 this purpose it is convenient to make the thermometer consist of two wires in parallel, as shown in Fig. VI, and to connect the alternating-current terminals 11 12 to the center of each wire, so that the alternating current 105 will not pass through the other resistances, forming the Wheatstone bridge, to which the thermometer is connected at 13 14. If the resistance consists of a fine platinum wire in a vertical tube containing mercury, changes of 110 level of the mercury will alter the length of wire exposed, and may therefore be recorded by the same apparatus. This application is useful for recording variations of barometric or steam pressure and variations of water-level, &c. If a pair of differential electrical thermometers be connected on either side of the bridge-wire, the record will give the difference of temperature. It is thus possible 115 to record in a single curve the difference of 120 temperature, for instance, between two stations at different altitudes or between the wet and dry bulb thermometers. Again, if one of the wires be blackened and both be exposed to radiation, such as sunshine or the 125 radiation of a furnace, the record represents 130 the intensity of radiation of the sun or of the furnace. It should be observed that all these different records may be obtained by means

of one single instrument by single changes in the electrical connections and in the apparatus with which it is associated.

The auxiliary pieces of apparatus, such as 5 platinum thermometers, &c., are separate attachments, and do not form essential parts of the apparatus. It is possible to use one single recording instrument in turn for all the different purposes specified.

- 10 10 I do not show a special description of the planimeter attachment for totalizing, which merely amounts to replacing the pen by a wheel rolling on a cone or disk. The pen and the planimeter-roller may be combined in one, 15 the curve-record being traced on the revolving disk by inking the roller of the planimeter, or both pen and planimeter may be separate, moving on separate surfaces, but both actuated by a common cord. These details, 20 which are common to so many instruments, are claimed in the combination with my special recording mechanism.

Having thus described my invention, the following is what I claim as new therein and 25 desire to secure by Letters Patent:

1. The combination of a bridge-wire, a contact movable along it, a recording device carried by the contact, a galvanometer, means for connecting its poles to the bridge-wire and 30 to the contact, and means actuated by the galvanometer for traversing the contact.

2. The combination of a bridge-wire, a contact movable along it, a recording device carried by the contact, a shunt, means for connecting its ends to the ends of the bridge-wire, a galvanometer, means for connecting 35 its poles to the shunt and to the contact, and means actuated by the galvanometer for traversing the contact.

- 40 3. The combination of a bridge-wire, a contact movable along it, a recording device carried by the contact, a galvanometer, means for connecting its poles to the bridge-wire, and to the contact, a series of auxiliary resistances, means for connecting them to the bridge-wire or resistance, and means actuated by the galvanometer for traversing the contact.

- 45 4. The combination of a bridge-wire, a contact movable along it, a recording device carried by the contact, a shunt, means for connecting its ends to the ends of the bridge-wire, a galvanometer, means for connecting its poles to the shunt and to the contact, a series of auxiliary resistances, means for connecting them to the bridge-wire, and means actuated by the galvanometer for traversing the contact.

- 50 5. The combination of a bridge-wire, a second wire parallel to it, a pair of contacts connected together and movable along the bridge-wire and the second wire, a recording device carried by the contacts, a galvanometer, means for connecting its poles to the bridge-wire and to the second wire, and means actuated by the galvanometer for traversing the contacts.

6. The combination of a bridge-wire, a second wire parallel to it, a pair of contacts connected together and movable along the 70 bridge-wire and the second wire, a recording device carried by the contacts, a shunt, means for connecting its ends to the ends of the bridge-wire, a galvanometer, means for connecting its poles to the shunt and to the second wire, and means actuated by the galvanometer for traversing the contacts.

7. The combination of a bridge-wire, a second wire parallel to it, a pair of contacts connected together and movable along the 80 bridge-wire and the second wire, a recording device carried by the contacts, a galvanometer, means for connecting its poles to the bridge-wire and to the second wire, a series of auxiliary resistances, means for connecting 85 them to the bridge-wire, and means actuated by the galvanometer for traversing the contacts.

8. The combination of a bridge-wire, a second wire parallel to it, a pair of contacts 90 connected together and movable along the bridge-wire and the second wire, a recording device carried by the contacts, a shunt, means for connecting its ends to the ends of the bridge-wire, a galvanometer, means for connecting 95 its poles to the shunt and to the second wire, a series of auxiliary resistances, means for connecting them to the bridge-wire, and means actuated by the galvanometer for traversing the contacts.

9. In an electrical recording apparatus the combination of a galvanometer-arm, means whereby it is kept in a state of gentle oscillation, a pair of contact-surfaces carried by it and a second pair of contact-surfaces against 105 which the first pair work.

10. In an electrical recording apparatus the combination of a galvanometer-arm, means whereby it is kept in a state of gentle oscillation, a pair of contact-surfaces carried by it, 110 a second pair of contact-surfaces against which the first pair work, means for rotating the second pair of surfaces and scrapers acting on them.

11. In an electrical recording apparatus, the 115 combination of a galvanometer-arm, a pair of contact-surfaces carried by it, a second pair of contact-surfaces against which the first pair work, means for rotating the second pair of surfaces and scrapers acting on them.

12. In an electrical recording apparatus, the combination of a galvanometer, a recording device, and a pair of motors controlled by the galvanometer and tending to move the recording device one in one direction and the other 125 in the other.

13. In an electrical recording apparatus, the combination of a galvanometer, a recording device, a pair of clock-motors tending to move the recording device one in one direction and the other in the other, brakes tending to stop the motors, and means operated by the galvanometer for taking off the brakes.

14. In an electrical recording apparatus, the

- combination of a galvanometer, a recording device, a pair of motors tending to move the recording device one in one direction and the other in the other, circuits closed by the galvanometer and controlling the motors, and switches in the circuits one at each end of the travel of the recording device and operated by it.
15. The combination of a bridge-wire movable longitudinally, means for clamping it in position, a contact movable along it, a recording device, a galvanometer, means for connecting its poles to the bridge-wire and to the contact, and means actuated by the galvanometer for traversing the contact.
16. The combination of an electrical recording apparatus, substantially as described, with a constant battery and a series of auxiliary resistances connected according to the 20 potentiometer method, for recording variations of voltage or current on a direct-current circuit, or for recording variations of temperature by means of a thermocouple or thermopile.
25. 17. The combination of a bridge-wire, a contact movable along it, a recording device carried by the contact, a galvanometer, means for connecting its poles to the bridge-wire and to the contact, a pair of clock-motors tending 30 to move the contact in opposite directions, brakes tending to stop the motors, and means operated by the galvanometer for taking off the brakes.
35. 18. The combination of a bridge-wire, a contact movable along it, a recording device carried by the contact, a shunt, means for connecting its ends to the ends of the bridge-wire, a galvanometer, means for connecting its poles to the shunt and to the contact, a 40 pair of clock-motors tending to move the contact in opposite directions, brakes tending to stop the motors, and means operated by the galvanometer for taking off the brakes.
45. 19. The combination of a bridge-wire, a contact movable along it, a recording device carried by the contact, a galvanometer, means for connecting its poles to the bridge-wire and to the contact, a series of auxiliary resistances, means for connecting them to the 50 bridge-wire, a pair of clock-motors tending to move the contact in opposite directions, brakes tending to stop the motors, and means operated by the galvanometer for taking off the brakes.
55. 20. The combination of a bridge-wire, a contact movable along it, a recording device carried by the contact, a shunt, means for connecting its ends to the ends of the bridge-wire, a galvanometer, means for connecting its poles 60 to the shunt and to the contact, a series of auxiliary resistances, means for connecting them to the bridge-wire, a pair of clock-motors tending to move the contact in opposite directions, brakes tending to stop the motors,
- and means operated by the galvanometer for taking off the brakes.
21. The combination of a bridge-wire, a second wire parallel to it, a pair of contacts connected together and movable along the bridge-wire and the second wire, a recording device 70 carried by the contacts, a galvanometer, means for connecting its poles to the bridge-wire and to the second wire, a pair of clock-motors tending to move the contacts in opposite directions, brakes tending to stop the 75 motors, and means operated by the galvanometer for taking off the brakes.
22. The combination of a bridge-wire, a second wire parallel to it, a pair of contacts connected together and movable along the bridge-wire and the second wire, a recording device 80 carried by the contacts, a shunt, means for connecting its ends to the ends of the bridge-wire, a galvanometer, means for connecting its poles to the shunt and to the second wire, 85 a pair of clock-motors tending to move the contacts in opposite directions, brakes tending to stop the motors, and means operated by the galvanometer for taking off the brakes.
23. The combination of a bridge-wire, a second wire parallel to it, a pair of contacts connected together and movable along the bridge-wire and the second wire, a recording device carried by the contacts, a galvanometer, means for connecting its poles to the bridge-wire or resistance and to the second wire, a 90 series of auxiliary resistances, means for connecting them to the bridge-wire, a pair of clock-motors tending to move the contacts in opposite directions, brakes tending to stop 100 the motors, and means operated by the galvanometer for taking off the brakes.
24. The combination of a bridge-wire, a second wire parallel to it, a pair of contacts connected together and movable along the bridge-wire and the second wire, a recording device carried by the contacts, a shunt, means for connecting its ends to the ends of the bridge-wire, a galvanometer, means for connecting its poles to the shunt and to the second wire, 105 110 a series of auxiliary resistances, means for connecting them to the bridge-wire, a pair of clock-motors tending to move the contacts in opposite directions, brakes tending to stop the motors, and means operated by the galvanometer for taking off the brakes.
25. In an electrical recording apparatus, the combination of a galvanometer-arm, contacts limiting its travel, and means for keeping it in a state of gentle oscillation.

The foregoing specification signed at Montreal, Dominion of Canada, this 9th day of March, 1898.

HUGH LONGBOURNE CALLENDAR.

In presence of—

HENRY FRY,
RONZO H. CLARK.
